UNITED STATES PATENT OFFICE.

THEODORE N. HANSEN, OF SEATTLE, WASHINGTON.

ATTACHMENT FOR REPRODUCING DEVICES.

Application filed June 6, 1927. Serial No. 196,912.

This invention relates to attachments for reproducing devices and is an improvement over my prior invention entitled "Reproducing devices" as described in an application filed May 24, 1926, Serial Number 111,- 443, and allowed March 26, 1927. The primary objects of my present invention are to provide, in conjunction with a transparent screen mounted on a stand and a sighting instrument, means whereby points may be marked on said screen by the operator while standing at a distance therefrom. The simple and efficient mechanical contrivances for effecting these objects in combination with certain structural details and arrangement of parts as more fully herein-after described constitute the novel features of my device.

In the drawings:

20 Figure 1 is a view in perspective showing the general application of the device as a whole;

Fig. 2 is a view in side elevation showing the principal features of the device;

25 Fig. 3 is a view in end elevation of the control box; and Fig. 4 is a view in front elevation of the marker bar and associated parts.

Referring to the drawings throughout 30 which like reference numerals designate like parts, the numeral 5 indicates a transparent screen that is preferably made of glass and set in a frame 6 that is mounted on a stand 7. The numeral 8 designates a sighting instrument that is mounted on a tripod 9 for horizontal and vertical movement. The numeral 10 indicates a control box that is mounted on a stand 11 and which will be more fully hereinafter described.

40 A metal plate 12 is fixedly secured to one side of the frame 6 and another plate 13 is mounted against the first named plate and adapted to revolve thereon by means presently set forth. A pipe 14 connects the control box 10 with the plate 13 and may comprise a plurality of sections as indicated by joints 15 so that the distance between said control box and plate may be altered 45 by removing or adding a section as desired.

One end portion of the pipe 14 is revolvably mounted in the forward end wall 16 of the box 10 and its extreme end is likewise mounted in a partition 17 that is spaced slightly to the rear of said end wall. A relatively large toothed wheel 18 inter-

posed between said end wall and partition is fixedly mounted on said pipe. A small pinion 19 in mesh with said toothed wheel has its axle 20 mounted in bearings secured to said wall and partition and a knob 21 on the end of said axle provides means whereby said pinion may be manipulated with the fingers.

The other end portion of the pipe 14 is fixedly connected with the plate 13 by four bracket arms 22 secured to said plate and to a collar 23 that is also secured to said pipe. It will now be obvious that by turning the toothed wheel 18 the plate 13 will revolve therewith and that slow motion of said plate may be caused by turning the pinion knob 21. A pin 24 slidably mounted on the partition 17 may be arranged in any suitable manner to jam between the 75 teeth of said wheel so as to hold the wheel and plate stationary at any desired point as will be understood.

A relatively long arm 25 is slidably arranged for longitudinal movement by being mounted in guides 26 secured to the plate 13. Said arm has a plurality of U standards 27 secured thereto in spaced relation. A marker bar 28 is pivoted at its outer end to standards 29 secured to said arm and a loop spring 30 also secured to said arm is adapted to normally hold said bar in a position parallel with said plate and against the bend of said U standards. The inner end of said marker bar is provided with an adjustable bracket 31 for holding the marker 32 which may be a pencil, pen, crayon or other device for marking points or making dots on the screen.

50 A slender shaft 33 extends entirely through the pipe 14 and may be jointed in conformity with said pipe so that its length may be altered therewith. The outer end of said shaft has its bearing in the rear wall 34 of the control box 10 and also in a partition 35 spaced slightly forward of said wall. A toothed wheel 36 interposed between said wall and partition is keyed to said shaft and a small pinion 37 is in mesh with said wheel. The axle of said pinion is mounted in bearings secured to said wall and partition and is provided with a knob 38 whereby same may be turned for slow motion with the fingers. A pin 39 slidably mounted on said end wall is adapted to jam between the teeth of said wheel for holding same stationary at any desired point.

The inner end of the shaft 33 has its bearing in the plates 12 and 13 in any suitable manner, as at 40 in Fig. 2, it being understood that the plate 13 is arranged to 5 revolve freely on same which serves as a pivotal support therefor. A small gear wheel 41 is keyed to said shaft close to the plate 13 and engages a rack 42 on the underside of the arm 25. Thus it will be apparent that by turning the wheel 36 said 10 shaft and gear will cause said arm together with the marker bar device to slidably move back or forth as desired.

The means for pivotally depressing the 15 marker bar 28 and causing the marker 32 to make an impression on the screen comprises a slender rod 43 that extends through the pipe 14 nearly its full length. Said rod may be jointed in conformity with said pipe 20 and shaft 33 so that its length may be altered therewith. The outer end of said rod terminates with in the control box 10 between the partitions 17 and 35 where it is provided with a handle 44. The inner end of said rod 25 terminates short of the pipe 14 and is bent at right angles to form a finger 45 which is always in engagement with the marker bar 28. A slot 46 is provided in the end of said pipe so that said finger may move back and 30 forth therein. It will now be obvious that in slidably moving said rod inwardly by means of its handle said finger will depress the marker bar and cause the marker to make a dot on the screen and upon releasing the 35 spring 30 will cause same to assume its normal position. The inner end of the arm 25 may be bifurcated or slotted as at 47 to serve as a guide for the marker 32 in its movements as will be readily understood.

40 In the practical use of my device the sighting instrument is set up and the screen is positioned between same and the landscape at the proper distance to intercept all the 45 lines of site that are to be included in the picture. The control box and stand are close to the sighting instrument so that the operator may reach same for manipulation while sighting through the instrument. The instrument is then sighted at a controlling 50 point, such as the top of the tree, and by means of the toothed wheel 18 the marker device is rotated to the proper alignment while the wheel 36 is rotated to slide said device back or forth until the point of the 55 marker 32 is directly over the point where

the line of sight intercepts the screen. Then by means of the handle 44 the marker bar 28 is depressed when its marker will make a dot on the screen at this point. This process is repeated until a sufficient number of 60 points have been reproduced on the screen for drawing in the picture.

It will be understood that my device may be used for enlarging as well. In this case the picture to be enlarged is placed between 65 the screen and level and the procedure is otherwise substantially the same.

Having thus described my invention, it being understood that minor changes may be resorted to in its construction without departing from its scope and spirit, what I claim and desire to secure by Letters Patent of the United States is:—

1. The combination with a screen and a sighting instrument, of an attachment for 70 reproducing devices comprising a control box, connecting means between said screen and box adapted for axial rotation, and a marker bar device arranged to be swung over the entire surface of the screen by axial rotation of the 75 pipe, and connecting means carried by said pipe for causing the bar to slidably move over the full length and width of the screen.

2. The combination with a screen and a sighting instrument, of an attachment for 80 reproducing devices comprising a control box disposed at a distance from the screen, a pipe connecting said screen and box arranged for axial rotation, a marker bar device adapted to be swung over the entire 85 surface of the screen by axial rotation of the pipe, and connecting means carried by said 90 pipe for causing the bar to slidably move the full length and width of the screen.

3. The combination with a screen and a sighting instrument, of an attachment for 95 reproducing devices comprising a control box disposed at a distance from the screen, a pipe connecting said screen and box adapted for axial rotation, a marker bar device arranged to be swung over the entire surface 100 of the screen by axial rotation of the pipe, connecting means between the box and bar for causing the bar to slidably move the full length and width of the screen, and connecting means between the box and bar for pivotally depressing said bar to a point of 105 contact with the screen.

In witness whereof, I hereunto subscribe my name this 30th day of May A. D. 1927.

THEODORE N. HANSEN.
